US0D1037439S

(12) **United States Design Patent** (10) **Patent No.:** **US D1,037,439 S**
(45) **Date of Patent:** **** Jul. 30, 2024**

(54) **OCULAR INJECTOR**

(71) Applicant: **EyePoint Pharmaceuticals, Inc.**,
Watertown, MA (US)

(72) Inventors: **Evan Hunter Williams**, Boston, MA
(US); **Michael W. Metz**, Providence, RI
(US)

(73) Assignee: **EyePoint Pharmaceuticals, Inc.**,
Watertown, MA (US)

(**) Term: **15 Years**

(21) Appl. No.: **29/823,357**

(22) Filed: **Jan. 17, 2022**

(51) **LOC (14) Cl.** **24-02**

(52) **U.S. Cl.**

USPC **D24/113**

(58) **Field of Classification Search**

USPC D24/112-114, 133, 210, 127-130, 108,
D24/150

CPC .. A61M 5/178; A61M 5/3146; A61M 5/3129;
A61M 5/3148; A61M 5/315

See application file for complete search history.

(57) **CLAIM**

The ornamental design for an ocular injector, as shown and described.

DESCRIPTION

FIG. 1 is a top front perspective view of an ocular injector; FIG. 2 is a bottom rear perspective view thereof;

FIG. 3 is a left side view thereof;

FIG. 4 is a front view thereof;

FIG. 5 is right side view thereof;

FIG. 6 is a rear view thereof;

FIG. 7 is a top view thereof; and,

FIG. 8 is a bottom view thereof.

The broken lines in the figures show portions of the ocular injector that form no part of the claimed design.

1 Claim, 5 Drawing Sheets
